UNITED STATES PATENT OFFICE.

AUGUST E. SCHUETTE AND JULIUS H. KINTZELE, OF ST. LOUIS, MISSOURI, ASSIGNEES,
BY MESNE ASSIGNMENTS, TO ST. LOUIS WASHING MACHINE COMPANY, A CORPORATION OF ILLINOIS.

GEARING.

1,265,530.

Specification of Letters Patent.

Patented May 7, 1918.

Application filed September 25, 1916. Serial No. 121,918.

To all whom it may concern:

Be it known that we, AUGUST E. SCHUETTE and JULIUS H. KINTZELE, both citizens of the United States, and residing at St. Louis, 5 in the State of Missouri, have invented a certain new and useful Improvement in Gearing, of which the following is a specification.

This invention relates to gearing, and 10 more particularly to gearings for washing machines of the motor driven type.

Washing machines of this type with which we have illustrated our improved gearing combined embody an outer casing, a washing element or drum within the casing, a wringer supported on the machine, and driving gearing for the drum and wringer. Since the drum is heavily loaded with clothes, and since it is necessary to impart to 20 the drum an alternating rotary movement in order to prevent twisting of the clothes, undue strain is thrown on the drum and the supporting means therefore, on account of the torque of the driving connections. The 25 driving mechanism is, moreover, necessarily somewhat complicated in order to perform its functions, and difficulty is, therefore, experienced in properly alining the elements of the driving mechanism, and in properly 30 lubricating the same.

One of the objects of this invention, therefore, is to provide a washing machine in which the driven elements and the driving gearing are so supported as to insure correct 35 alinement, and so as to prevent the incidental strains from affecting the casing.

Another object is to provide novel driving gearing which is arranged as a unit, so as to be readily removable from the machine, 40 which is constructed to permit lubrication of parts, and which is positive and certain in its action, so as to prevent undue strain on and breakage of the parts.

Another object is to provide a washing 45 machine which is simple in construction and operation, cheap to manufacture, and which possesses great strength and durability consistent with lightness in weight.

Further objects will appear from the detail description taken in connection with the accompanying drawings, in which:

Figure 1 is a rear elevation of a machine embodying this invention;

Fig. 2 is an end elevation;

Fig. 2^a is a section on the line 2^a—2^a;

Fig. 2^b is a section on the line 2^b—2^b;

Fig. 3 is an enlarged detail plan view of

the driving gearing;

Fig. 4 is a section on the line 4—4, Fig. 3;

Fig. 5 is a detail, partly in section, of one 60 of the bevel gears;

Fig. 6 is an end view of Fig. 5;

Fig. 7 is a section on the line 7—7, Fig. 6; and,

Fig. 8 is a section on the line 8—8, Fig. 1. 65

Referring to the accompanying drawings, and more particularly, to Figs. 1, 2 and 2^a, 1 designates the body of a casing having ends 2 seamed to the body to form a self-contained structure, that is, to form a structure which is complete in itself. A pair of end frames 3, of substantially circular form, and having each an inwardly projecting flange 4 and radial arms 5 running to a center support 6, engage the ends of the casing 75 with the flanges 4 taking over the casing, so that the ends of the casing will be terminally supported by these end frames. These end frames are of pressed metal, the flanges and the ribbed arms 5 resulting in a structure which has great rigidity compared with its weight. Each end frame has attached thereto a pair of legs 7, each leg, at its point of engagement with the frame, branching laterally, as shown at 8, and being flanged, 85 as shown at 9, to embrace the end frame and form a rigid connection therewith. These legs are removably attached to the end frames by means of bolts 10. Rods 11 and 12 connect these legs at their upper and 90 lower ends. Brackets 120 are attached to the end frames, these brackets being also preferably of pressed metal construction and supporting a beam 13 which is rigidly secured in position between the brackets by a 95 tension rod 14 passing through the brackets, and thus firmly connecting the end frames at their upper ends.

Arranged within the casing and attached to the center supports 6 are bearing brackets 100 15, which removably support the trunnions 16 of a drum 17, this drum being preferably constructed and removably supported. A cover 18 is mounted on arms 19, which in turn are pivoted on the bearings 15 at 20, 105 so that the cover can swing back and forth to permit access to and removal of the drum. The casing is provided with a drain cock 21.

Mounted on a bearing 25 attached to the center support 6, on one of the end frames, 110 is a stub shaft 26 which has a detachable engagement with the trunnion of the drum,

Fixed to this shaft is a disk 27 having a circular recess 28 terminating in a stop 29, and recessed as shown at 30. This disk has a hub 31, upon which is mounted the hub 32 of a gear wheel 33. This gear wheel has attached thereto a flange 34 provided with an axially projecting lug 35 working in the recess 30. Springs 36 are located in the recess 28, and bear against the lug 29 on the disk 27, and the lug 35 on the flange 34. A flanged collar 37 fixed to the shaft 36 holds the parts in assembled relation.

A bracket 38 is attached to the leg 7 by a bolt 39 engaging a slot in the bracket, and on this bracket is mounted an idler 40 meshing with the gear 33.

The driving gearing comprises a unit 45, consisting of a housing provided with a removable cover 46, and having legs 47. Angle iron brackets 48, resting upon the cross bars 12, and clamped between the legs by these cross bars, form supports for the housing. For this purpose the housing is provided with bolts 41 resting on the brackets 48, so that the housing is adjustable along the brackets, and nuts 42 on the bolts clamp the housing in adjusted position. The shaft 49 of this driving gearing has a pinion 50 meshing with the idler 40. Mounted on this housing is a bracket 51 supporting an electric motor 52, whose shaft 53 has a universal coupling connection with the main drive shaft 54 of the driving gearing.

Referring now more particularly to Figs. 3, 4 and 5, the main drive shaft 54, which is mounted in bearings 55 in the housing, has fixed thereto a worm 56 meshing with a worm wheel 57 loosely mounted on a shaft 58 supported in bearings 59 in the housing. This worm wheel has clutch teeth 60 meshing with clutch teeth on a clutch sleeve 61 splined to the shaft 58, and this clutch sleeve is shifted by a fork 62 mounted on a rock shaft 63 having an arm 64 outside of the housing, connected by a link 65 with a bell crank shifting lever 66 pivoted on the end frame 3.

Loosely mounted on the shaft 58 are a pair of sleeves 67, and in turn loosely mounted on these sleeves are bevel gears 68 meshing with a bevel gear 69 on the shaft 49, which is supported in bearings 70 in the housing. The sleeve 67 and the bevel gear 68 mounted thereon have radially projecting lugs 71 and 72 respectively, and the lug 71 has fixed therein an arcuate bar 73 passing loosely through the lug 72 and having mounted thereon a spring 74 between the lugs 71 and 72, a cotter pin 75 passing through the end 60 of the bar keeping the parts together. Arranged within the sleeve 67 are a pair of plungers 76, the reduced ends 77 of which form clutch jaws. These jaws are projected by springs 78 bearing against the pins 76 and 85 against screws 79. The jaws 77 are adapted

to be engaged by jaws 80 on a clutch sleeve 81, splined to the shaft 58 and shifted by an arm 82 pivoted at 83 on a bracket 84 fixed to the housing. The arm 82 has integral therewith an arm 85, which in turn has joined thereto at 86 an arm 87 loosely passing through a swivel member 88 provided with lugs 89 engaging recesses in a bracket 90. A spring 91 positioned between a collar 92 on the arm 87 and the swivel member 88 exerts a pressure on the joint and serves to move the arm 85 laterally in either direction when the toggle formed by the arms 85 and 87 is broken as hereinafter described. Journaled between the bracket 84 and a bearing lug projecting upwardly from the bottom of the housing is a worm wheel 93 meshing with a worm 94 fixed to the shaft 58. This worm wheel has fixed thereto or formed thereon cams 95 and 97, adapted to engage a cam roll 96 on the arm 85.

Operation of the clutch sleeve 61 through the bell crank lever 66 will operate to connect and disconnect the shaft 58 with and from the main drive shaft 54. Rotation of the drive shaft 58 will continuously rotate the worm wheel 93 and its attached cam 95, and will also rotate the clutch sleeve 81. Assuming the parts to be in the position shown in Fig. 3, in which the cam 95 moving in the direction of the arrow has shifted the arm 85 to a position so that the clutch sleeve 81 will be in midposition, this movement has straightened the toggle and placed the spring 91 under compression. Further movement of the cam will move the arm 85 to the right, and a slight movement over the dead center position of the toggle will break the toggle to the right, and the spring 91 will then act to quickly engage the clutch sleeve 81 with the jaws of the lower sleeve 67 and connect the lower bevel gear 68 with the shaft 58, thereby causing the clutch bevel gear, through its gear connection with the bevel gear 69, to drive the shaft 49. The shaft 49 will be driven in that direction until the cam lug 97 engages the cam roll 96. This cam lug 97 will first operate to straighten the toggle and then move it over dead center in the other direction, moving the arm 85 to the left, thereby placing the spring 91 under compression, and, after the toggle joint has passed over dead center, the spring 91 will again operate to quickly throw the clutch sleeve 81 upwardly toward the upper sleeve 67, to cause the jaws 80 to engage the jaws on this clutch sleeve and connect the upper bevel gear 68 with the shaft 58, thereby causing the shaft 58, through the gear connections 68 and 69, to drive the shaft 49 in the reverse direction.

It will thus be seen that this shifting mechanism operates to positively retract the clutch shifting jaws and to yieldingly engage the same with a quick snap action,

thereby resulting in a positive disengagement and a rapid engagement of the clutch jaws, and preventing wear on these jaws.

It will be seen that with this mechanism 5 means are provided for imparting to the drum an alternating rotary movement, the gearing connection being such that the drum is rotated a plurality of revolutions before reversing. The reversal of the heavy drum, 10 of course, throws considerable strain on the driving gearing. It is for this reason that the yielding connection between each of the gears 68 and its supporting sleeve 67 are provided. It will be seen that, upon engagement 15 of a sleeve 67 with the clutch sleeve 81, the torque is transmitted through the spring 74, which compresses and thus takes up the shock at the point of reversal. This spring is, of course, strong enough to 20 take the load without undue compression. To still further take up the shock at the point of reversal, a yielding connection is made between the gear 33 and the drum, through the springs 36. These springs act 25 as additional cushions to take up the shock, whereby all strains on the gear teeth are avoided. It is, of course, obvious that the yielding connection shown in Fig. 8 could 30 be bodily applied to the idler 40 by a similar connection, and a detail description or illustration of such a construction is, therefore, entirely superfluous, since it is entirely obvious.

The shaft 54 has fixed thereto a worm 100, 35 which meshes with a worm wheel 101 having a bearing in the housing, and provided with a stub shaft 102 having a universal joint connection with a shaft 103, in turn having a universal joint connection with the 40 shaft 104 of the wringer driving gearing, which is mounted in a housing 105. This wringer gearing may be of the construction as shown in Patent No. 1,082,551. The driven shaft 106 of the wringer gearing is 45 connected to drive the wringer 107 supported on the cross beam 13. The controlling arm for the wringer gearing is shown at 108.

It will thus be seen that the invention 50 accomplishes its objects. A washing machine is produced which is simple in construction and operation. The casing and end frames, while of light construction, are entirely rigid, and in view of the fact that the casing 55 is self-contained, and all parts supported from the end frames instead of from the casing, this casing can be made of thin metal. By mounting the driving gearing in a housing and by attaching thereto the motor, this motor and housing can be removed 60 and replaced as a unit, thereby enabling the parts of the gearing to be accurately machined without requiring excessive time for lining up the shafts and the bearings. It 65 will be readily seen, by reference to Figs. 1

and 2, that the gearing can be readily removed as a unit by simply disconnecting the operating rod 65 and the shaft 103 at their lower ends. The adjustable mounting of the bracket 38, moreover, furnishes a quick 70 means for alining and adjusting the idler 40 with respect to the gear 50. By raising the gearing and the housing, this housing can be filled with oil and grease, so that the 75 gearing can run in oil, thereby resulting in perfect and continuous lubrication. Moreover, by mounting this unit below the casing, it is not only firmly supported, but any dripping of oil will not reach the clothes, 80 thereby preventing soiling.

It is obvious that various changes may be made in the details of construction without departing from the spirit of this invention, and it is, therefore, to be understood that this invention is not to be limited to the specific details shown and described.

Having thus described the invention, what is claimed is:

1. Gearing of the character described, comprising a drive shaft, a pinion attached 90 to the drive shaft, a driven shaft, a pair of gears loose on the driven shaft meshing with said pinion, a clutch movable to positions to clutch said gears alternately to said driven shaft, a lever movable to actuate said clutch into alternate engagement with said gears, a pair of cams, means for actuating said cams by said driven shaft for imparting initial movement in opposite directions to said lever, and a spring acting on said lever 100 to impart the final movements to said lever in both directions.

2. Gearing of the character described, comprising a drive shaft, a pinion rigid on the drive shaft, a driven shaft, two gears 105 loosely mounted on the driven shaft meshing with the pinion on the drive shaft, a clutch movable to clutch said gears alternately to said driven shaft whereby said driven shaft will be rotated alternately in 110 opposite directions by said drive shaft, a lever for moving said clutch to clutch said gears alternately to said driven shaft, a pair of cams operable to impart initial movement to said lever in opposite directions, a support on which said cams are mounted, means for actuating said support from said driven shaft, and an additional actuator acting on said lever to impart final movements thereto in opposite directions after the initial movements have been imparted to said lever by 120 said cams.

3. Gearing of the character described, comprising a drive shaft, a pinion rigid on said drive shaft, a driven shaft, two gears 125 loosely mounted on said driven shaft, a clutch movable to positions to clutch said gears alternately to said driven shaft, a lever for moving said clutch to positions to clutch said gears alternately to said driven 130

- shaft, cams for imparting initial movements to said lever alternately in opposite directions, an arm pivoted to said lever, a spring encircling said arm and being placed under compression by the initial movements of said lever by said cams, and a pivoted abutment for said spring against which said spring is held in imparting the final movements to said lever in opposite directions
- 10 after the initial movements have been imparted to said lever by said cams.
4. Gearing of the character described, comprising a drive shaft, a pinion rigid on said shaft, a driven shaft, two gears loosely mounted on said driven shaft meshing with said pinion, a clutching member for controlling said gears, a toggle connected to said clutch member, cams adapted to impart initial movements in opposite directions
- 15 to said clutching member, and a spring acting on said toggle to impart the final movements to said clutching member in opposite directions.
5. Gearing of the character described, comprising a drive shaft, a driven shaft, gearing connecting said shafts, a clutching member for controlling said gearing, a lever connected to said clutching member for shifting the same, a toggle connected to said lever, a spring in connection with said toggle acting to impart the final movements to said lever in opposite directions after said toggle is broken, and cams arranged to impart initial movements to said lever to shift the same
- 30 in alternately opposite directions.
6. Gearing of the character described, comprising a drive shaft, a driven shaft, a pinion rigid on one of said shafts, gear wheels loose on the other shaft meshing with said pinion, a clutching member for controlling said gearing, a lever connected to said clutching member for actuating the same in opposite directions, a toggle in connection with said lever, a cam roll on said toggle, cams arranged to operate against said roll to impart initial movements to said lever in alternately opposite directions, a spring having one end abutting against the arm on said lever and encircling the other arm, a pivoted abutment for said spring whereby said spring is compressed when said arms are moved by said cams, said spring being arranged to impart the final movements to said arms, and a device operated by said driven shaft for operating said cams.
- 40
- 45
- 50
7. Gearing of the character described, comprising a drive shaft, a driven shaft, bearing connecting said shafts, a clutching member for controlling said gearing, a toggle connected to said clutching member, a worm on one of said shafts, a worm wheel operated by said worm, cams on said worm wheel for imparting initial movements to said toggle in alternately opposite directions, a spring, means for energizing said spring by the movement of said toggle when said toggle is moved by said cams, and means whereby

said spring will impart the final movements to said toggle to complete the shifting of 65 said clutching member.

8. Gearing of the character described, comprising a drive shaft, a driven shaft, gearing connecting said shafts, a clutching member for controlling said gearing, a lever for 70 shifting said clutching member, a toggle in connection with said lever, a worm on one of said shafts, a worm wheel engaging said worm, cams on said worm wheel arranged to engage said toggle to impart the initial 75 movements to said toggle and to said lever in alternately opposite directions, and a spring energized by the initial movements of said toggle by said cams arranged to impart the final movements to said toggle and said lever. 80

9. Gearing of the character described, comprising a drive shaft, a driven shaft, a pinion rigid on one of said shafts, gear wheels loose on the other shaft meshing with said pinion, a clutching member for controlling 85 said gearing, a lever connected to said clutching member for actuating the same in opposite directions, an arm in connection with said lever, a toggle arm in connection with the arm of the lever, a cam roll on one of said arms, cams arranged to operate against said roll to impart initial movements to said lever in alternately opposite directions, a spring having one end abutting against the arm on said lever and encircling the other arm, a pivoted abutment for said spring whereby said spring is compressed when said arms are moved by said cams, said spring being arranged to impart the final movements to said arms, and a device operated 90 by said driven shaft for operating said cams.

10. In driving gearing of the class described, a drive shaft, a driven shaft, gearing connecting said shafts, a clutching member for controlling said gearing, a toggle connected to said clutching member, a spring acting to break said toggle, a cam roll on said toggle, and a cam adapted to engage opposite sides of said roll to alternately shift said clutching member in opposite directions. 105

11. In driving gearing of the class described, a drive shaft, a driven shaft, gearing connecting said shafts, a clutching member for controlling said gearing, a toggle connected to said clutching member, a spring acting to break said toggle, a worm on one of said shafts, a worm wheel engaging said worm, and a cam on said worm wheel adapted to engage said toggle to shift said clutching member. 115

. In testimony whereof we affix our signatures this 29 day of April, 1916.

AUGUST E. SCHUETTE.
JULIUS H. KINTZELE.
